CLAIM

We claim the ornamental design for a blind mate waveguide flange, as shown and described.

DESCRIPTION

FIG. 1 is a top front right perspective view of a blind mate waveguide flange;

FIG. 2 is a bottom rear left perspective view thereof;

FIG. 3 is a front elevational view thereof;

FIG. 4 is a right side elevational view thereof;

FIG. 5 is a rear elevational view thereof;

FIG. 6 is a left side elevational view thereof;

FIG. 7 is a top plan view thereof; and,

FIG. 8 is a bottom plan view thereof.

The broken lines shown represent portions of the blind mate waveguide flange that form no part of the claimed design.
